UNITED STATES PATENT OFFICE.

WILLIAM R. BARTON, OF BRIDGEWATER, MASSACHUSETTS, ASSIGNOR OF
ONE-HALF TO GEORGE C. HAMMOND, OF CENTRAL FALLS, R. I.

EDGE-IRON.

SPECIFICATION forming part of Letters Patent No. 236,760, dated January 18, 1881.

Application filed November 24, 1880. (Model.)

To all whom it may concern:

Be it known that I, WILLIAM R. BARTON, a citizen of the United States, residing at Bridgewater, in the county of Plymouth and State of Massachusetts, have invented new and useful Improvements in Edge-Irons, of which the following is a specification.

This invention relates to a tool for burnishing the edges of boot and shoe soles after they have been planed, its object being to give to such a tool an adjustable burnishing-surface, the extent of which may be readily arranged to correspond to the plane which has been previously used, and to obviate inconvenience in handling on account of heat from the burnishing-block.

My improved edge-iron is designed, especially, for use in connection with an improved edge-plane, using bits of various widths, for which I have filed an application for patent bearing even date with this.

In the accompanying drawings, Figure 1 is a front view, Fig. 2 an outer-edge view, Fig. 3 a rear view, and Fig. 4 an inner-edge view, of my improved edge-iron. Fig. 5 is a perspective view of the burnishing-block, its holder and adjustable guard detached. Fig. 6 is an outer-edge view of the tool, illustrating a modified construction of the same.

The letter A indicates the handle; B, the burnishing-block, and C its holder, which is composed of the broad guard-arm d, narrow holding-arm e, and the connecting-plate f, from which projects a suitable shank to fit in a socket in the handle. The burnishing-block tapers toward its top on two sides, and its other sides fit between the guard-arm d and holding-arm e, the latter fitting in a groove, g, formed in said block, which is secured to the arm by means of a screw, h, passing through a hole in the arm and into the block. The block is of such thickness that its opposite side does not touch the guard-arm when secured to the holding-arm, nor does its top touch the plate f, so that there is a free passage of air in one side and over the top of the block, to prevent heat from being communicated to said guard-arm and plate f.

The burnishing-face b of the block B terminates at one end in a flange, b', which should be similar in shape to the flange of the plane used in finishing, and the other or guard flange, i, is adjustable, and is provided with a slotted lug, k, projecting at about a right angle, and

extending laterally to fit upon a shoulder, l, 55 formed on the block, and upon which it is adjustable, a suitable screw passing through the slot in the lug and into the block serving to hold guard-flange in position.

Upon the rear surface of the block B is inscribed a scale, m, the graduations of which correspond to the widths of the cutting-edges of planing-tools, and enable the flange i to be so adjusted that the burnishing-face of the edge-iron will properly follow the edge planed by a given-sized plane or bit.

In the modification shown in Fig. 6 a recess, n, is formed longitudinally in the top of the block to permit the passage of air, which prevents any undue communication of heat to the plate f and the guard-arm, against which the lower portion of the operator's hand rests.

The burnishing-block, being separable, can be heated and secured in its holder without trouble.

75

What I claim is—

1. The holder C, constructed with the broad imperforate guard-arm d, narrow holding-arm e, and connecting-plate f, in combination with the burnishing-tool, detachably secured at one side to the holding-arm, and disconnected and separated from the guard-arm at the opposite side to provide an air-space, all substantially as shown and described.

2. The combination, with the detachable burnishing-block having the flange b' at one end, of the guard-flange i, extending across the face of the burnishing-block, and constructed with the laterally-projecting slotted lug k, bearing upon one side of said block, and adjustably connected thereto by a set-screw, substantially as described.

3. The combination, with the holder C, having the holding-arm e, and the burnishing-block, having the vertical side groove, g, in which said holding-arm is secured, and provided with the side shoulder, l, of the guard-arm i, extending across the face of the burnishing-block, and provided with a laterally-projecting slotted arm, k, resting on the shoulder l, and adjustably secured in position, substantially as described.

In testimony whereof I have hereunto set my hand in the presence of two subscribing witnesses.
